UNITED STATES PATENT OFFICE.

ALBERT A. HUSEBY, OF CHICAGO, ILLINOIS.

MUSIC-ROLL CARTON.

1,290,750.

Specification of Letters Patent.

Patented Jan. 7, 1919.

Application filed March 4, 1918. Serial No. 220,146.

To all whom it may concern:

Be it known that I, ALBERT A. HUSEBY, a citizen of the United States, residing at Chicago, in the county of Cook and State 5 of Illinois, have invented certain new and useful Improvements in Music-Roll Cartons, of which the following is a specification.

This invention relates to improvements in 10 cartons, and has reference more particularly to that class of cartons used to contain music rolls for self-playing instruments, such as player-pianos.

The boxes or cartons in which these music 15 rolls are usually stored or filed when not in use are frequently placed in superposed rows in a cabinet or rack, and, in order to get at any particular desired roll, it is often necessary to first withdraw from the cabinet 20 the cartons lying above it. To obviate this inconvenience, it has heretofore been proposed to provide the carton with a hinged end cover or closure which may be dropped so that the music roll may be withdrawn 25 endwise, and it has further been proposed to provide an attachment to the end cover which, through engagement with the spool of the roll, acts to partially withdraw the latter as the cover is opened. My present 30 invention relates to this latter class or type of cartons, and has for its principal object to provide a cover-actuated roll-withdrawing device characterized by greater simplicity, efficiency and economy than those 35 at present known. Another object is to provide a device of such a character that the weight of the music roll, when in the carton, will hold the cover or lid in closed position. Other objects and advantages of 40 the invention will be readily understood and appreciated by those skilled in the art from the following detailed description taken in connection with the accompanying drawing, wherein I have illustrated a practical and approved embodiment of the invention, and in which—

Figure 1 is a vertical longitudinal section, showing a music roll in the carton, and with the cover closed;

50 Fig. 2 is a similar view, broken off at the rear end, and showing the cover open and the music roll partly withdrawn;

Fig. 3 is a fragmentary view in vertical longitudinal section showing a metal hinge;

55 and

Fig. 4 is a front elevation of Fig. 3.

Referring to the drawing, 5 designates the rectangular body of the carton, and 6 designates the end cover or lid that is attached at its lower edge to the forward edge 60 of the bottom wall of the body by a hinge member 7 (Figs. 1 and 2) of cloth, leather or like flexible material. 8 designates the body and 9 the heads of a spool on which is wound the music record sheet 10. 65

Attached to the inner side of the cover 6 by one or more rivets 11, which also secure the hinge member 7 to the cover, is the shank 12' of a short inwardly extending hook 12 that, when the music roll is in place 70 in the carton and the cover is closed, engages behind and beneath the peripheral edge of the head 9 of the spool that lies adjacent to the cover 6 in the manner clearly shown in Fig. 1. Secured by a 75 rivet 13 to the outer side of the cover, preferably adjacent to and projecting beyond its upper free edge, is a pulling tab 14. When the cover is opened by pulling outwardly and downwardly on the tab 14, the 80 roll is partly withdrawn by the hook 12 to a position in which it may be readily grasped by the hand and completely withdrawn, leaving the empty carton in its original position in the cabinet or rack. When the music roll 85 is replaced to the position shown in Fig. 2, and the cover is closed, as shown in Fig. 1, the weight of the forward end of the roll, resting on the hook 12, holds the cover in closed position in an obvious manner. 90

The modification shown in Figs. 3 and 4 differs from the form of the invention illustrated in Figs. 1 and 2 only in employing a metallic hinge in lieu of a cloth or like flexible one-piece hinge member. 95 Here 15 and 16 designate the two leaves of the hinge secured to the cover and body by rivets 17 and 18 respectively, and jointed by the usual hinge-pin or pintle 19; and 20 designates the spool-engaging hook that 100 may be attached to or formed integral with the hinge-leaf 15. In both of the constructions shown it will be observed that the spool-engaging hook is rigidly secured to the cover and necessarily partakes of the 105 angular movements of the latter in opening and closing.

It is believed that the structure, mode of use, and advantages of the invention will be readily apparent to those skilled in the 110 art from the foregoing description and the accompanying illustration. Detail changes

may of course be made without substantially altering the structural principle or lessening the practical utility of the device, and within the spirit and purview of the appended claims.

I claim:

1. A music roll carton having a hinged end cover, said cover having attached thereto an inwardly extending hook engaging behind and supporting the head of the spool lying adjacent to said cover when the latter is closed whereby said roll is partially withdrawn when the cover is opened.

2. A music roll carton having a hinged cover, said cover having rigidly attached thereto adjacent to its hinged edge an inwardly extending hook engaging behind and supporting the head of the spool lying adjacent to said cover when the latter is closed whereby said roll is partially withdrawn when the cover is opened.

Copies of this patent may be obtained for five cents each, by addressing the "Commissioner of Patents, Washington, D. C."

3. The combination of a rectangular carton body, an end cover hinged at one edge to said body, an inwardly extending hook rigidly secured to said cover and engaging behind and supporting the head of a spool in said body lying next to said cover, and a pulling tab secured to the outer side of said cover for opening the same.

4. The combination of a rectangular carton body, an end cover hinged at its lower edge to the lower wall of said carton body, an inwardly extending hook secured to the inner side of said cover adjacent to its hinged edge and engaging behind and supporting the head of a spool in said body lying next to said cover when the latter is closed, and a pulling tab secured to the outer side of said cover and projecting beyond a free edge of the latter.

ALBERT A. HUSEBY.
